UNITED STATES PATENT OFFICE.

GEORGE SMITH, JR., OF NEW YORK, N. Y., ASSIGNOR OF ONE-FOURTH TO
LEANDER H. THORN AND JAMES R. LANGDON, BOTH OF SAME PLACE.

DIFFERENTIAL PULLEY.

SPECIFICATION forming part of Letters Patent No. 293,281, dated February 12, 1884.

Application filed September 18, 1883. (No model.)

To all whom it may concern:

Be it known that I, GEORGE SMITH, Jr., of New York city, county of New York, and State of New York, have invented certain new and useful Improvements in Differential Pulleys, of which the following is a full, clear, and exact description, reference being had to the accompanying drawings, and to the letters of reference marked thereon.

10 My invention has relation to that class of pulleys or pulley-blocks commonly known as "differential pulleys;" and the object of my said invention is to produce a simple, durable, cheap, and efficient pulley of the class 15 named, wherein the load will be held at any point without danger of slipping, the continuous rope or line wound and unwound without wearing or abrading one portion against the other, and without unnecessary friction, 20 and on which the rope or line may be quickly and easily replaced by a new one, whenever desired. To accomplish all of this my improvements involve certain novel and useful 25 peculiarities of construction, relative arrangements or combinations of parts, and principles of operation, all of which will be herein first fully described, and then pointed out in the claims.

The mere winding and unwinding of a line 30 or chain simultaneously, but with varying rapidity, in order to produce the differential resultant movement, is a principle well understood. Heretofore in the construction of pulley-blocks employing this principle the 35 chain has been commonly employed, and in this form it is observed that after long use the links of the chain become stretched and worn, and the furrows formed in the sheaves become worn, so that it is impossible to substitute a new chain in the old block or adapt a 40 new block to receive the old chain, in consequence of which the entire device becomes useless as soon as one of its parts is worn or broken. Where the rope or flexible line has 45 been employed, (in this class,) when one part of it reaches the margin of the sheave it rides up upon the adjacent portion, and practically prevents the further hoisting or lowering 50 of the load, besides producing an excessive wear upon the line. To obviate this it has

been proposed to employ separate and independent lines, and also to lead the lines about the two sheaves, so that parts thereof cross between the axes of the sheaves, also producing wear, limiting the movements of the load, 55 and rendering it difficult to replace the line in its intricate windings, as well as increasing the cost of the specially-devised sheaves and their fittings. I obviate these several objections to the differential-pulley block, as heretofore constructed, and secure various advantages by the simple construction and arrangements below explained.

In the accompanying drawings, forming part of this specification, Figure 1 is a side elevation of a differential-pulley block arranged for operation in accordance with my invention, and involving the principles thereof, the front plate of the upper or main block being omitted. Fig. 2 is a front elevation, and Fig. 3 a central vertical section, of the apparatus shown in Fig. 1. Fig. 4 is a sectional view of the upper and lower sheaves of the main block detached from the frame, indicating a variation in the number of grooves in the sheaves, 75 and different ways in which the sheaves may be cast, all within the limits of my invention; and Fig. 5 is a front elevation of these two sheaves with the line wound thereon in accordance with my invention. Fig. 6 is a plan 80 of the axles of the two sheaves in the differential block, showing a slight inclination which it is preferred to give them, one with respect to the other.

In all these figures like letters of reference, 85 wherever they occur, indicate corresponding parts.

A A are the sides of the differential block, which may be of any material and any size or shape. These plates sustain the axles of the 90 upper and lower sheaves therein, and are connected with any ordinary suspending device, as the hook B.

C C' is the upper sheave, and D D' the lower sheave, both provided with grooves to accommodate the rope or line, and both having one section larger or of greater diameter than the other, as indicated. In each sheave both sections must move together, and when the pulley is in operation both sheaves move together. 100

The relative sizes of these two sheaves (each considered as a whole) may vary to any extent desired; but it is important and necessary, in order that the line may run smoothly and 5 properly, that the circumference of the two sections of the two sheaves shall bear the same relative proportions one to the other—that is, as the circumference of section C is to the circumference of section C', so must circumference 10 of section D be to circumference of section D'. Without this the line would not pay on and off the sheaves in the proper manner. The diameters of the sheave-sections are of course in the same proportions as their 15 circumferences, and these diameters are most conveniently measured by taking the distance between the centers of the rope-groove at top and bottom of the sheave. The rope or line is wound about the two sheaves so proportioned, from outside to outside of the pair, never crossing between them. The grooves are to keep the moving portions of the rope 20 free and clear of each other, and it should be observed that there must be one more groove 25 (in which the rope moves) in each of the sections of the upper sheave than in the corresponding sections of the lower sheave. This is necessary in order that the rope may lead properly. Of these grooves there may be two 30 in each of the lower sections and three in each of the upper sections; or these numbers may be correspondingly increased to any desired extent, though they cannot be decreased and lead and hold the rope in accordance with my 35 invention. The rope is continuous—that is, after being properly located in the pulley-block and in the fall, its ends are spliced, and it may be of any length so as to insure the proper travel of the fall upon which the load 40 is applied. It should also be observed that it is immaterial upon which section of the rope the fall is applied, inasmuch as both portions are made to move in equal degrees, though, for convenience, I call one part the "hand" portion and the other the "fall" portion.

E represents the rope, and F the fall, which 45 may be of any character. The rope is wound as follows: Starting from any point—as, for instance, the bottom of the loop in the hand portion, Figs. 2 and 3—it is carried up over the outside groove in section C, down under the outside groove in section D, up over second groove in C, down under second groove in D, up over third groove in C, down under 50 third groove in D, up over fourth groove in C, down behind to the fall, up under the fall-pulley, over first groove (at the right) in C', down under first in D', up over second in C', down under second in D', up over third in C', down under third in D', up over fourth in C', then down behind to the starting-point, where it is spliced. The same system of winding is followed in the case where the lower sheave has 55 only two grooves in each section thereof, and the upper three, as indicated in Figs. 4 and 5, and it is also followed, however the number of

grooves may be varied. Being so arranged, when one part of the hand portion is pulled down the fall is compelled to rise, but with a different velocity, depending upon the variations 70 between the diameters of the two sections of the upper sheave, upon principles well understood. By pulling down upon the other portion the fall will descend, with like difference in velocity. The greater the number of grooves 75 in the sheaves, the greater will be the certainty with which the load may be held (without slipping) after being elevated. The lower sheave is only employed as a guide for the rope, and the rope must lead from one sheave to the other 80 in a slightly-inclined direction, as best indicated in Fig. 5. To obviate any cramping tendency which might result from this inclination, I locate the axes of the sheaves so that they cross each other, substantially as indicated in Fig. 6. These axes are (supposing the pulley to be suspended freely) in separate planes, and their relative inclinations are very 85 slight, as indicated.

When the pulley is in use, one portion of the 90 hand-rope runs up loosely to its groove in the upper sheave, and would be liable to buckle thereon, or not lead fairly thereto, unless provided with a suitable guide. To supply this I employ a pair of light rollers, a a, mounted 95 upon the frame of the pulley-block in any light springs, as b b, the tension of which may be adjusted by suitable screws, c. These rollers insure the proper leading of the rope, by pressing thereon with only sufficient power to keep 100 the rope taut and in proper line, but not hard enough to produce any appreciable resistance to the workings of the pulley.

The sheaves may be of cast metal, and hollow or solid, as may be desired. One made 105 hollow is shown in Fig. 5. They may be cast with the grooves in them, and have only to be cleaned out to be made ready for application. The construction is found in practice to be simple and well calculated to answer the several 110 purposes and objects of the invention, as previously set forth. If the rope becomes worn, it has only to be replaced by another, which may be quickly and easily done, or, if broken, it may be spliced—advantages which will be 115 readily appreciated. The use of the rope has many advantages over the chain, notably its 120 cheapness, lightness, greater flexibility, and greater ease and smoothness of operating and of handling.

Having now fully described my invention, what I claim as new, and desire to secure by Letters Patent, is—

1. In a differential pulley of the character herein set forth, the upper and lower sheaves, 125 grooved for the reception of the rope, each sheave being composed of two sections movable together, the sections in the two sheaves bearing the same relative proportions to each other, substantially as shown and described.

2. In a differential pulley, the combination, 130 with the two grooved sheaves, proportioned as

explained, and the fall, of the operating-rope wound over and under the larger sections of the two sheaves from outside to outside, under the fall, and over and under the smaller sections of the two sheaves from outside to outside, and spliced, substantially as shown and described.

3. In a differential pulley having the two grooved sheaves, proportioned as explained, the rope wound thereon, as explained, and the fall, and the spring-actuated rollers mounted upon the frame of the pulley-block, and serving to guide the hand portions of the rope, substantially as set forth.

4. In a differential pulley, the upper and lower sheaves, grooved for the reception of the rope, the axes of the two sheaves being inclined with respect to each other, substantially as shown and described.

In testimony that I claim the foregoing I have hereunto set my hand in the presence of two witnesses.

GEORGE SMITH, JR.
